 Amery, deceased

Application April 19, 1943, Serial No. 483,653
 In Great Britain December 31, 1941

3 Claims. (Cl. 60—54.5)

This invention comprises improvements in or relating to hydraulic remote control apparatus.

It is an object of the invention to provide means whereby movements of an actuator at a transmitting station produce corresponding movements of an actuated member at a receiving station and in which reaction of the actuated member on the actuator is reduced or minimised.

It is known to transmit movement by means of hydraulic remote control apparatus comprising, at a transmitting station, an actuator and piston-and-cylinder mechanism operated by the actuator to impel hydraulic liquid, corresponding piston-and-cylinder mechanism at a receiving station to be actuated by said liquid and conduit connections between the transmitting and receiving stations for the liquid and the present invention relates to apparatus of this type. In some instances the apparatus comprises two pistons and cylinders at the transmitting station connected by two conduits to a corresponding pair of pistons and cylinders at the receiving station, but preferably in the use of the present invention there is only one piston and cylinder at each station and a single interconnecting pipe. Under the expression "piston-and-cylinder mechanism" there is intended to be included such equivalents as bellows mechanism which, under the effect of hydraulic pressure, will produce movement of an actuated part to an extent proportional to the hydraulic flow.

According to the invention, in apparatus of the kind described, valve means are provided at the transmitting station or the receiving station or both which are normally closed, but are automatically opened by movement at the transmitting station of the actuator so that the hydraulic liquid is locked against movement except under the influence of the actuator.

The apparatus may be of the type in which a single piston and cylinder at the transmitting and receiving stations are interconnected by a single pipe and return movements of the piston at the receiving station are effected by a yielding return member such as a spring or liquid under pressure.

Preferably the valve means which close the intercommunication conduit are such as to yield under a predetermined pressure so that while the actuated member resists stiffly up to a predetermined point, the application of force to it beyond this degree will permit it to yield.

The invention may be applied to hydraulic control devices for all kinds of purposes including, for example, the brakes of vehicles, the distant

control of parts on motor vehicles such as throttles and hydraulic jacks, the operation of a petrol gauge from a float, or the like; the invention may also be applied to all kinds of remote control devices on aircraft such as throttles or the opening of doors, the release of projectiles, the operation of flaps and rudders and the like. The irreversible feature of the control makes the apparatus particularly useful for operating rudders and flaps, or for operating brakes on wheels. In the latter case fatigue is obviated as the brake will remain on at a predetermined pressure until the operator completely releases the brake pedal, without the necessity of maintaining full pressure with the foot. Indeed in all kinds of apparatus it becomes possible to substitute a temporary application of force for a maintained one.

The following is a description, by way of example, of one distant control in accordance with the invention and of modifications thereof:

In the accompanying drawings:

Figure 1 is a longitudinal section through a transmitting station;

Figure 2 is a similar view of a receiving station;

Figure 3 is a detail.

The apparatus comprises the transmitting station, Figure 1, connected to a receiving station, Figure 2, by means of a metal pipe 11. The transmitting station consists of a cylinder 12 connected by a valve box 13 to the pipe 11. The valve box comprises an outer plate 14 which carries a union 15 for attachment to the pipe 11; there is also an inner diaphragm 115 which is separated from the outer plate 14 by a space 16. In the diaphragm 115 are two ports 17, 18. The port 17 is closed by a lift valve 19 which is located in the space 16 and opens under the effect of pressure in the cylinder 12 against the action of a light spring 20.

In the cylinder 12 is a piston 21 and movement of the piston inwards in the cylinder 12, that is to say in the direction towards the diaphragm 115, will open the lift valve 19 but a return movement of the liquid from the pipe 11 into the cylinder 12 is not permitted by the valve 19.

The port 18 is closed by a disc valve 22 which rests on the cylinder side of the diaphragm 115 and opens inwardly into the cylinder. The disc valve 22 is closed by a spring 23 of predetermined strength which bears on the back of the disc valve and is supported by a bracket 24 secured to the diaphragm 115. Thus liquid cannot flow back from the pipe 11 into the cylinder 12 except through the disc valve 22, and such flow is prevented from occurring as long as the valve 22 is

held closed. The strength of the spring 23 is made sufficient to hold the valve 22 closed against the effect of such pressure in the pipe 11 as can be applied by the reaction against movements of the actuated member at the receiving station.

The disc valve 22 has secured to its cylinder a tubular stem 25 which extends axially through the cylinder 12 and which enters and slides in a passage 26 extending through the centre of the piston 21. The base part of the stem 25 is somewhat enlarged as shown at 27 and fits the walls of the passage 26 closely. The passage 26 is sufficiently long to enable the piston 21 to execute its full working stroke while still in contact with the enlarged end portion 27 of the valve stem 25. The portion 27 joins the stem 25 with a shoulder as shown at 28. An abutment plate 29 in the form of a washer is secured to the end of the piston 21 so that the hole in the centre of the abutment plate 29 surrounds the valve stem 25 closely.

The piston 21 is connected by a connecting rod 30 to a crank 31 and the crank has a spindle 131 which passes through one of the side walls 32 which extend from the cylinder 12 upwardly on each side of the connecting rod 30. The crank is provided with an actuating lever 33 so that the piston 21 can be moved up and down in the cylinder 12 to any extent desired. At one side of the cylinder 12 there is an oil reservoir chamber 34 and in the wall of the cylinder there is a port 35 which connects the reservoir chamber to the interior of the cylinder. The port 35 is located in such a position that it is uncovered by the piston at the outer extremity of its stroke but is covered at all other times.

For reasons which will hereinafter appear the lever 33 on the crank 31 is made so as to be radially slidable through the hub of the crank and takes the form of a rod having a handle 36 at one end and a cam roller 37 at the other. The cam roller works over a cam surface 38 secured to the interior of one of the side walls. The cam 38 is so shaped that as the lever 33 is moved angularly to operate the crank and to drive the piston 21 inwards, the lever slides through the hub of the crank 31 and the leverage of the lever over the hub is increased. Contact of the cam roller with the cam 38 during return movement is ensured by a spring 39.

At the receiving station the mechanism comprises a cylinder 40 containing a piston 41 which is connected by a connecting rod 42 to a crank 43 on a crankshaft 44; the piston 41 and cylinder 40 are made of similar dimensions to the piston 21 and cylinder 12 at the transmitting station, although these dimensions may be different if desired. The pipe 11 is connected to an end cover 45 of the cylinder 40. The crank 43 carries an arm 46 which constitutes an actuated member of the transmission and which may be coupled to any device which is to be operated, such, for example, as an engine throttle, an aeroplane rudder, a flap or other parts as mentioned hereinbefore.

The piston 41 is provided with a strong return spring 47 so that it tends always to return, against the action of any pressure in the hydraulic connections, to the position in which the piston is moved inwardly to its greatest extent.

In the operation of this device, if the actuating lever 33 is moved over at the transmitting station the piston 21 will be driven into the cylinder 12 to a corresponding degree. This will force out hydraulic liquid through the valve 19 and through the pipe 11 into the cylinder

40 where the liquid will cause the piston 41 to move outwardly and operate the actuated member 46 to an extent which precisely corresponds to the extent of movement of the actuating lever 33. This movement is resisted by the spring 47 to an increasing extent as the stroke proceeds but the increasing force required to overcome the spring is balanced by the increased leverage of the handle 36 over the crank 31. As soon as the movement of the lever 33 ceases, movement of the actuated member 46 ceases also. Any tendency of the actuated member 46 to return is prevented by the valves 19 and 22, for the valve 19 will remain shut against any return pressure, and the valve 22 will be held closed by the spring 23; a relatively small force exerted by the spring 23 can oppose a considerable force on the actuated member 46 because the area of the disc valve 22 is small in relation to the area of the piston 41.

20 When the actuated lever is moved in the return direction it will draw the piston 21 outwardly and produce suction in cylinder 12. This tends to lift valve 22. The pressure which is kept on the liquid in the pipe 11 by the spring 47 also tends to lift valve 22, and so does the dash-pot effect of liquid trapped between the shoulder 28 and abutment plate 29. The valve 22 will be lifted off its seat by the combined effects of these three forces and the piston 41 with the actuated member 46 will then be able to return. When the piston 21 reaches the outer end of its stroke it uncovers the port 35 and permits the liquid in the cylinder 12 to be replenished if any leak has occurred. Moreover the abutment disc 29 engages the shoulder 35 on the stem 25 and ensures that the valve 22 is positively lifted off its seat so that equalisation of pressure and synchronism of the actuator and the actuated member are automatically effected.

Referring now to Figure 3, this shows a modified construction in which the cylinder 12 and piston 21 with their associated parts are similar to what has already been described except that the valve means connecting the cylinder 12 and the pipe 11 are modified in the following respects: 40 The valve 22 is replaced by a valve 50 having a long stem 51 which is capable of sliding in the space 26 of the piston 21. A long compression spring 52 which passes through the space 26 tends to keep the valve 50 on its seat. A clutch casing 53 is provided on the piston 21 around the stem 51 and contains a number of triangular clutch segments 54 which are pressed downwardly by a spring 55 and which rest upon an inclined conical face 56 in the bottom of the clutch casing 53. The clutch segments are therefore pressed by the spring 55 against the sides of the stem 51 and when the piston 21 is moved upwardly the clutch segments tend to draw the valve 50 upwardly with the piston against the action of the spring 52. 50 This opens the valve 50 and facilitates the movement of the parts, because the opening of the valve no longer depends solely upon suction in the cylinder 12. The upward movement of the valve 50 is limited by a stop 57 engaging a bracket 58. 60 At any stage of the outward movement a very slight return movement of the actuator 33 will cause the valve 50 to seat and will lock the parts.

The use of the long spring 52 to hold the valve 50 on its seat ensures that the valve is held closed by a force which is increased the further the piston 21 is forced into the cylinder 12. This increase may be made to follow the same ratio as the increase in the return pressure of the spring in the receiving station. Thus the locking action of the valve 50 in preventing undesired re-

turn movement of the actuated member 46 at the receiving station will at all points of the stroke have the same excess value over the force exerted by the return spring 47 of the receiving station and the locking effect will not vary at different points of the stroke.

Means may also be provided for compensating for the effects of variation of temperature. The result of temperature variations is to lead to variations between the positions of the actuator and the actuated member. As the temperature increases a certain amount of liquid is forced out of the intercommunication pipe into the receiving cylinder and tends to move the actuated member accordingly.

I claim:

1. Hydraulic remote-control apparatus comprising a transmitter cylinder, a piston therein, an actuator for said piston, a receiver cylinder, a receiver piston therein, an actuated member operatively connected to said receiver piston, a pipeline interconnecting the said two cylinders so that liquid in the pipeline will cause motion of one piston to be communicated to the other, a lift-valve opening under liquid flow from the transmitter to the receiver and shutting against flow in a contrary direction, a second lift-valve in parallel with the first and shutting against liquid flow from the transmitter to the receiver, a spring to hold said second lift-valve closed against pressure exerted from the receiver up to a predetermined amount, a stem on the said second lift-valve and a friction device on the transmitter piston in engagement with said stem to open said second lift-valve against said spring.

2. Hydraulic remote-control apparatus comprising a transmitter cylinder, a piston therein, an actuator for said piston, a receiver cylinder, a receiver piston therein, an actuated member operatively connected to said receiver piston, a pipeline interconnecting the said two cylinders so

that liquid in the pipeline will cause motion of one piston to be communicated to the other, a lift-valve opening under liquid flow from the transmitter to the receiver and shutting against flow in a contrary direction, a second lift-valve in parallel with the first and shutting against liquid flow from the transmitter to the receiver, a spring to hold said second lift-valve closed against pressure exerted from the receiver up to a predetermined amount, a clutch operatively connecting the piston of the transmitter to the said second valve so as to open the valve whenever any outward movement of the piston relatively to the cylinder occurs and thereafter to permit further movement of the piston to take place relatively to the valve, for the purpose described.

3. Hydraulic remote-control apparatus comprising a transmitter cylinder, a piston therein, an actuator for said piston, a receiver cylinder, a receiver piston therein, an actuated member operatively connected to said receiver piston, a pipeline interconnecting the said two cylinders so that liquid in the pipeline will cause motion of one piston to be communicated to the other, a lift-valve opening under liquid flow from the transmitter to the receiver and shutting against flow in a contrary direction, a second lift-valve in parallel with the first and shutting against liquid flow from the transmitter to the receiver, a spring to hold said second lift-valve closed against pressure exerted from the receiver up to a predetermined amount, a stem on the said second lift-valve and a friction device on the transmitter piston in engagement with said stem to open the valve whenever the piston moves outwardly relatively to the transmitter cylinder.

GEORGE AMERY.
